(57) **CLAIM**

We claim an ornamental design for the line light illumination lamp, as shown and described.

DESCRIPTION

FIG. 1 is a front elevational view of a first embodiment of a line light illumination lamp showing our design;
FIG. 2 is a rear elevational view of the first embodiment thereof;

FIG. 3 is a right side elevational view of the first embodiment thereof;
FIG. 4 is a left side elevational view of the first embodiment thereof;

FIG. 5 is a top plan view of the first embodiment thereof;
FIG. 6 is a bottom plan view of the first embodiment thereof;

FIG. 7 is a perspective view of the first embodiment thereof;
FIG. 8 is a front elevational view of a second embodiment of a line light illumination lamp showing our design;

FIG. 9 is a rear elevational view of the second embodiment thereof;
FIG. 10 is a right side elevational view of the second embodiment thereof;
FIG. 11 is a left side elevational view of the second embodiment thereof;

FIG. 12 is a top plan view of the second embodiment thereof;
FIG. 13 is a bottom plan view of the second embodiment thereof; and,

FIG. 14 is a perspective view of the second embodiment thereof.
